UNITED STATES PATENT OFFICE.

WILLIAM WILLIAMS, OF TORONTO, ONTARIO, CANADA.

COMBINED SAFETY CATCH AND POINT PROTECTOR FOR BROOCH PINS.

1,406,708.

Specification of Letters Patent. Patented Feb. 14, 1922.

Application filed June 9, 1921. Serial No. 476,255.

To all whom it may concern:

Be it known that I, WILLIAM WILLIAMS, a subject of the King of Great Britain, a resident of the city of Toronto, in the county 5 of York, in the Province of Ontario, Canada, have invented certain new and useful Improvements in Combined Safety Catches and Point Protectors for Brooch Pins, of which the following is the specification.

10 My invention relates to combined safety catches and point protectors for brooch pins and the object of the invention is to devise a simple and effective safety catch that can be readily applied to the brooch and which 15 will prevent the liability of the pin becoming disengaged therefrom.

My invention consists of a combined safety catch and point protector constructed and arranged substantially as hereinafter 20 more particularly described and illustrated in the accompanying drawing in which:

Fig. 1 is a side elevation of a brooch showing my device applied thereto.

Fig. 2 is an enlarged cross sectional view 25 thereof through the line 2—2 Figure 1.

Fig. 3 is a cross sectional view of a modified form of my device.

Fig. 4 is a plan view of a blank from 30 which my device is constructed, and

Fig. 5 is a similar view to Figure 4 showing the safety catch portion turned up at right angles to the point protector portion prior to forming such safety catch portion into the required shape.

35 Like characters of reference indicate corresponding parts in the different views.

1 is the brooch having the usual pin 2 hinged thereto by the hinge 3. 4 is the central portion of my catch. 5 and 6 are the 40 upper and lower portions thereof. 7 is the pin point protector.

In carrying out my invention I make use 45 of a blank as shown in Figure 4. I then turn the safety catch portions 5 and 6 at right angles to the pin point protector portion 7 as is clearly shown in Figure 5. The free ends of the portions 5 and 6 are then suitably bent into the position shown in Figure 2.

50 It will be seen that when such portions are bent the lower portion 6 forms a closed loop whereas the upper portion 5 forms an open loop, the distance between the ad-

jacent sides of these loops being less than the diameter of the pin 2.

55 In applying the pin to the safety catch it is only necessary to shove the same between the free ends 5 and 6 thereof. As the portion 6 is enclosed it will be seen that the pin will not be permitted to be inserted 60 into the loop formed thereby but will be inserted into the open loop formed by the portion 5 as is clearly shown in Figure 2 of the drawing.

The portion 6 is suitably secured to the 65 brooch 1 by soldering the same thereto.

In the modification shown in Figure 3 it will be seen that the whole safety catch is turned over and the central portion 4 of the safety catch secured to the brooch 1.

70 From the above description it will be seen that I have devised a simple and effective safety catch which the pin will not be liable to become disengaged therefrom and further in which the portion 7 effectually covers 75 the point of the pin.

In addition it will be seen that the combined safety catch and pin point protector being constructed of one piece can be readily and cheaply manufactured.

80 What I claim as my invention is—

1. The combination with a brooch and the pin thereof, of a safety catch suitably secured to said brooch, said safety catch comprising a central portion having the free 85 ends thereof bent over to form loops, the distance between the adjacent sides of the loops being less than the diameter of the pin, one of the loops being closed and the other loop being open to receive the pin. 90

2. The combination with a brooch and the pin thereof, of a safety catch suitably secured to said brooch, said safety catch comprising a central portion having the free ends thereof bent over to form loops, 95 the distance between the adjacent sides of the loops being less than the diameter of the pin, one of the loops being closed and the other loop being open to receive the pin and means for protecting the pin point. 100

3. The combination with a brooch and the pin thereof, of a safety catch suitably secured to said brooch, said safety catch comprising a central portion having the free ends thereof bent over to form loops, the distance between the adjacent sides of the loops 105

being less than the diameter of the pin and a pin point protecting portion formed integrally with the central portion and adapted to be bent at right angles thereto for covering the pin point.

4. A combined safety catch and pin point protector comprising a central portion having its free ends suitably bent into open and closed loops respectively and a pin point 10 protector portion formed integrally with the central portion and adapted to be turned over at right angles thereto to abut the free ends when formed into loops.

5. A combined safety catch and pin point

protector comprising a central portion having its ends bent over to form opposed loops, and a pin point protecting portion formed integrally with the central portion and adapted to be turned over against the edges of the loops.

6. A blank for forming a combined safety catch and pin point protector comprising a central portion having opposed strip shaped ends formed integrally therewith, and a laterally extending portion formed integrally 25 with the central portion.

WILLIAM WILLIAMS.
